DIESEL ENGINE COMPANY, OF ST. LOUIS, MISSOURI, A CORPORATION OF MISSOURI.

STARTING MECHANISM FOR COMBUSTION-ENGINES.

1,254,774.

Specification of Letters Patent.

Patented Jan. 29, 1918.

Application filed April 12, 1912. Serial No. 690,234.

To all whom it may concern:

Be it known that I, ALFRED BÜCHI, engineer, a citizen of the Republic of Switzerland, residing at Winterthur, Canton of Zurich, Switzerland, have invented the following-described new and useful Improvements in Starting Mechanism for Combustion-Engines.

The invention is an improvement in combustion engines, its object being to provide air-starting mechanism for such engines combined in simple and reliable manner with means for safeguarding the engine against excessive cylinder pressures, and to this end the invention consists in the combination, arrangement and mode of operation of the several parts as hereinafter set forth and pointed out in the claims.

The drawings represent the invention in schematic form in such manner as will enable those skilled in this art to understand and practice the invention.

Figures 1 and 2 represent respectively two positions of valve-gearing control according to this invention, and

Figs. 3 and 4 represent the principles of invention applied in the same manner to multi-cylinder engines.

Referring first to Figs. 1 and 2, the engine cylinder is marked 1 and its piston 2, it being understood that the engine can be of any type or form desired. In addition to the usual ports and passages leading to or from the combustion space of the cylinder and which are omitted for clearness, the cylinder is provided with a special passage through which starting air can be admitted or through which excess cylinder pressure can be vented, according to the position of adjustment of the valve mechanism controlling such passage. In the present instance the passage is formed by a valve-casing 3, a pipe or similar communication 4, and a valve-casing 5. The valve-casing 3 contains a valve 12 closing against or toward the cylinder and loaded by the pressure of a spring 6, which pressure is imparted to the valve through the link and lever connections indicated by 7. The spring tension is sufficient through such connections to maintain the valve closed against all normal cylinder pressures but permits it to open to abnormal or dangerous pressures. The design of this safety valve is not important so long as its construction enables it to serve the function

just stated. The valve-casing 5 is in communication through a port or pipe 8, with the atmosphere, or a region of equivalently low pressure, and through the starting air-pipe 10 is in communication with a source of compressed air, herein employed for starting the engine, or driving it. The valve 11 of this valve casing is shiftable between two positions therein, one of which is indicated by Fig. 1 and the other by Fig. 2. In Fig. 1 the position of the valve 11 is such that it opens the passage-way 3, 4, 5, 8 permitting excess cylinder pressure to raise the valve 12 and escape when necessary through such passage to the atmosphere. In Fig. 2 the passage-way just mentioned is closed by the valve 11 and a communication from the pipe 4 to the air-pipe 10 is about to be opened. The means for producing this shift of position of the valve 11 is connected to open the loaded valve 12 at the same time, so that the compressed air entering pipe 4 may thus have access to the cylinder for starting or driving the engine by compressed air instead of combustion. The connections and operating means for this purpose comprise the push member 13, or equivalent device, arranged for operation either manually or by power, as desired. In the one case it can be operated by the use of the screw-shaft 14 and hand-wheel 15 of obvious arrangement, and in the other by means of air pressure which can be taken from the air-pipe 10, the push member being supplied with a piston 16, and a cylinder 17, to which air may be admitted and exhausted, under control, by the proper manipulation of the valves 18 and 18^a. The operation of the said control member, whether regarded as the hand-wheel or the controlling valves, results in the opening of the valve 12, through the thrust of the push member 13 against the loading spring 6, and the resulting movement of the connections 7, but obviously such opening of the valve can be accomplished in other ways. Some one of the members that are thus moved by the operation of the control member, and preferably the push member 13, bears the fulcrum, a shifting fulcrum, of a rocker lever 19, which is driven by a cam or eccentric 21 on an engine-driven cam shaft 22, and connected by a link 23 to the valve 11, so that such valve, when in the position indicated by Fig. 2 will be caused to open and close the communication from 110

the starting-air pipe 10 to the cylinder in proper phase with the engine piston and according to the requirements of starting or driving the engine. The valve 11 can be 5 of any desired type within this invention, being herein shown as a double-ended slide or piston valve with functions which are well-known as well as obvious from the diagrams. The shift of push member 13 and 10 hence of the fulcrum 20, shifts the connections 19 and 23 so as to move the slide valve 11 to the position indicated by Fig. 1, where it no longer performs its functions of a starting valve, while the functions of the 15 valve 12 as a safety valve are restored. It will be noted that the engine is thus controlled by two valves, in series relation and jointly controlling a common entrance to the engine cylinder, whereby the same entrance 20 or passage may alternately serve as an escape passage and an air inlet. It will be further noted that within the range of movement of the push member 13, or other member under the operator's control, the position 25 of the shifting fulcrum 20 may be varied as desired without closing the valve 12, so that thereby the degree of admission of starting air may be varied in accordance with requirements. The stroke of the slide valve 30 also, may be varied as required or necessary for properly fulfilling its starting functions, and as will be well understood by those skilled in the art.

In Figs. 3 and 4, in which the same principle of control is applied to multi-cylinder engines, the valve 24 of each cylinder corresponds to the loaded valve 12 in Figs. 1 and 2, each, however, being in this case supplied with its own loading spring 25 and 35 with duplicate opening connections 26, whereby by the actuation of the push member 13, will cause the simultaneous and positive opening of both valves against their loads. The valves 27 and 28 correspond respectively 40 to the slide valve 11 in Figs. 1 and 2, being also slide valves. These valves are hollow and may operate in the same valve casing through the end of which they are adapted to open communication between pipes 4 and 45 the atmosphere as indicated, when the fulcrum 20 is shifted to the safety escape position. In the other position, being that indicated in Fig. 3, the said valves are appropriately operated to admit the starting 50 air from pipe 10 to each cylinder at or about dead center. The valve-actuating rocker-levers 19, however, in this case are operated by the engine-driven shaft 22, through link-motion reversing-gear of familiar design, 55 whereby the starting valves may be properly operated and controlled for either direction of running of the engine, it being understood, of course, that the link motion operates such valves in proper alternation with 60 each other. In Figs. 3 and 4 the valve 30 is

adapted to close the supply of starting air when not needed.

In both the exemplifications of the invention the starting air is exhausted through the normal exhaust valves or ports 31, but 70 may be exhausted to the atmosphere back through the inlet pipes 4, by a proper modification of the gearing.

I claim:

1. In apparatus for starting combustion 75 engines by compressed air, the combination with an engine cylinder of a valve for escape of excess pressure therefor and means for admitting compressed air through such valve for starting the engine.

2. In apparatus for starting combustion engines by compressed air, the combination with an engine cylinder, of a loaded valve therefor closing toward the same and provided with communications respectively representing an escape for excess cylinder pressure and an inlet thereto for compressed air, valve mechanism operating to close one of such communications and open the other, and means for suitably controlling the admission of compressed air through said inlet to start the engine therewith.

3. In combination with a cylinder of a combustion engine, valve mechanism providing an escape for excess pressure from 95 the cylinder and a compressed air inlet to it, controlling means whereby either of such communications may be closed and the other opened, and engine-driven means for controlling the passage of compressed air through said compressed air inlet for starting the engine.

4. In a combustion engine, valve mechanism controlling passages representing an air inlet to the engine cylinder and an escape 105 for excess pressure therefrom, said mechanism being shiftable to close one passage and open the other, a loaded valve in the escape passage, and a device for shifting said valve mechanism.

5. In a combustion engine, valve mechanism controlling communications respectively representing an escape for excess pressure from the cylinder and an air inlet thereto, and comprising a valve member shiftable between closing and opening positions with respect to said escape passage, and means for operating said member in its escape-closing position to admit compressed air to the cylinder at or about the engine dead 115 center.

6. In a combustion engine, a cylinder provided with a loaded valve for escape of excess pressure and having connections for admitting starting air through it, means for opening the valve against its load and valve-mechanism controlled by said valve opening means adapted for timing the admission to the cylinder of such starting air.

7. In a combustion engine, a compressed air 130

- inlet to the engine cylinder controlled by two valves in series relation, said passage being also adapted to provide an escape for excess cylinder pressure, in combination with 5 a common control member for both valves whereby said passage may serve either of the said functions.
8. In a combustion engine, a compressed air inlet to the engine cylinder adapted to 10 serve also as an escape for excess cylinder pressure, and controlled by two valves, one of such valves being engine-driven and constituting a starting valve and the other constituting a valve for escape of excess pressure in combination with a control member 15 for both valves and serving to suspend and restore the respective functions thereof.
9. In a combustion engine, a passage for admitting compressed air to the engine cylinder for starting the engine, provided with suitable valve mechanism whereby the same passage may serve also as a safety escape from the cylinder, and a control member for such valve mechanism operative to vary the 20 extent of compressed air admission.
10. In a combustion engine, a passage for admitting compressed air to start the engine and provided with suitable valve mechanism, whereby the same passage may serve 25 also as a safety escape for the cylinder pressure, a control member for such mechanism and fluid pressure means for operating the said control member.
11. In a combustion engine, a passage 30 communicating with the engine cylinder and provided with two series-related valves adapted for relative adjustment whereby the same passage may serve either as a compressed air inlet for starting the engine or 35 a safety escape for excess cylinder pressure, in combination with driving connections for operating one of said valves in phase with the engine, and a control member for such driving connections adapted to open the 40 other valve.
12. In a combustion engine a passage 45 communicating with the engine cylinder and two series-related valves therefor, driving connections for operating one of said 50 valves in phase with the engine and a movable member variably controlling such driving connections and adapted by its movement to operate the other valve.
13. In air-starting apparatus for combustion engines, a passage communicating with the engine cylinder and controlled by two 55 valves, one being a valve for escape of excess pressure and the other an air inlet valve, reversible means for operating the latter valve to start the engine in motion in either direction and a control member for said valve adapted for suspending and restoring the function of the escape valve.
14. In air-starting apparatus for combustion engines, a passage controlled by two 60
- series-related valves, the one most remote from the cylinder having alternate positions in which it connects said passage respectively to the atmosphere and to a source of compressed air, and reversible engine-driven 70 connections for operating said valve as a starting valve, in its latter position, combined with means for operating the other valve.
15. In air-starting apparatus for multi-cylinder combustion engines, a passage to each cylinder controlled by two valves, one of said valves for each cylinder being shiftable between alternate positions in which it connects such passage respectively with the 75 atmosphere and with a compressed air source, and means common to all of the shiftable valves for moving the same from one position to the other.
16. In air-starting apparatus for combustion engines, a passage controlled by two valves, the one most remote from the cylinder being a slide valve and having alternate positions in which it connects said passage, respectively with the atmosphere and with 80 a source of compressed air, in combination with driving connections for actuating said valve as a starting valve in its latter position and means for shifting it from one position of operation to the other. 85
17. In air-starting apparatus for multi-cylinder combustion engines, a passage to each cylinder controlled by a valve for escape of excess pressure, means for suspending the function of such valves and means 90 for admitting and controlling the admission of compressed air through such valves for starting the engine. 95
18. In an engine of the character described, the combination of a cylinder, a combined starting and safety valve whose face is exposed to the pressure existing within the cylinder to cause it to open outwardly on a predetermined cylinder pressure, an outlet port through which the contents of 100 the cylinder may escape when the valve is opened in response to cylinder pressure, means for opening the valve to admit starting fluid to the cylinder, and a device to prevent said fluid from escaping through 105 the outlet port when said valve is opened by said means. 110
19. A valve for admitting motive fluid to the cylinder of an internal combustion engine, combined with means for positively 115 opening it to admit said fluid, a spring for holding it yieldingly closed, whereby it can open automatically to relieve an abnormal pressure in said cylinder, a connection from a source of fluid pressure and an escape passage to a region of lower pressure, and means for opening the fluid pressure connection and closing the escape passage. 120
20. In an internal combustion engine, the combination of a valve the face of which is 125

- exposed to cylinder pressure and moves outwardly when said pressure exceeds a predetermined value, a spring which normally holds the valve on its seat against the cylinder pressure, an outlet port through which the contents of the cylinder may pass when the valve is opened in response to cylinder pressure, and a piston actuated by compressed fluid which opens the valve against the action of the spring to admit said fluid to the cylinder and also closes the outlet port.
21. In an internal combustion engine, the combination of a valve the face of which is exposed to cylinder pressure and moves outwardly when said pressure exceeds a predetermined value, a spring which normally holds the valve on its seat against the cylinder pressure, an outlet port through which the contents of the cylinder may pass when the valve is opened in response to cylinder pressure, a connection for supplying starting fluid, and means operative to open the valve against the action of the spring and to close the outlet port when said fluid is admitted to the cylinder.
22. The combination with an internal combustion engine having a cylinder and working piston of a combined starting and relief valve therefor comprising a valve casting, an outwardly opening valve therein which is exposed to cylinder pressure, fluid actuated means for opening said valve to admit starting fluid to the cylinder, a passage connecting the interior of said valve casting to a region of lower pressure, and means for closing said passage during the admission of starting fluid.
23. In an internal combustion engine, the combination of a cylinder, a working piston, a spring-seated combined starting and relief valve, a casing therefor, and means for alternately connecting the casing to the supply of starting fluid to start the engine and to a region of lower pressure during normal operation.
24. In an internal combustion engine, the combination of a cylinder having a port, a connection from a source of fluid pressure for starting and a relief passage to a region of lower pressure, and means controlling communication between said port and the fluid pressure connection on the one-hand or the relief passage on the other hand, said means including a valve commanding the cylinder port and having a spring for holding it yieldingly closed against cylinder pressure and means for opening it against the action of the spring for starting.
25. Starting and relief valve mechanism for an internal combustion engine cylinder comprising two valves and two passages, one of said passages leading from a source of compressed starting fluid and the other being a relief passage leading to a region of lower pressure, one of the valves being shiftable to open one of the passages and to close the other and the other valve being yieldingly spring-closed against cylinder pressure and having means for opening it when starting fluid is admitted.
26. Starting and relief valve mechanism for an internal combustion engine cylinder comprising two valves and two passages, one of said passages leading from a source of compressed starting fluid and the other being a relief passage leading to a region of lower pressure, one of the valves controlling the starting fluid passage and having means for operating it in proper time for starting, and the other valve being yieldingly spring-closed against cylinder pressure to vent the cylinder through the relief passage in event of said pressure exceeding a predetermined value, and means whereby the latter valve is opened and the relief passage closed in starting.
- In testimony whereof, I have signed this specification in the presence of two witnesses.
- ALFRED BÜCHI.
